GRAB RAIL FOR SWIMMING POOLS

Jack A. Berg, Van Nuys, Calif., assignor to Marine Swimming Pool Equipment Company, North Hollywood, Calif., a corporation of California

Filed May 17, 1965, Ser. No. 85,296

Term of patent 14 years

(Cl. D13—1)

FIG. 1.

FIG. 2.

FIG. 3.

FIG. 4.

FIG. 1 is a side elevation of a grab rail embodying my design;

FIG. 2 is a front elevational view of the same;

FIG. 3 is a rear end elevational view of the same; and

FIG. 4 is a top plan view of the same.

I claim:

The ornamental design for a grab rail for swimming pools, as shown.
